UNITED STATES PATENT OFFICE.

FRANK CALVO, OF WATERBURY, CONNECTICUT.

CALLUS PROTECTOR AND ARCH SUPPORT.

Application filed January 19, 1929. Serial No. 333,549.

This invention relates to foot appliances, and more particularly to a combination callus protector and arch support.

One object of this invention is to provide a device of the above nature which may be accurately adjusted at any desired position along the length of the sole.

A further object is to provide a device of the above nature which will be simple in construction, inexpensive to manufacture, easy to install and adjust, compact, ornamental in appearance, and very efficient and durable in use.

With these and other objects in view there has been illustrated on the accompanying drawings one form in which the invention may be conveniently embodied in practice.

Fig. 1 represents a bottom plan view of the invention showing the callus-protecting and arch-supporting pad in operating position.

Fig. 2 is a similar bottom view of the same with the pad removed.

Fig. 3 is a transverse sectional view of the same taken along the line 3—3 of Fig. 2.

Fig. 4 is a fragmentary longitudinal sectional view of the same taken along the line 4—4 of Fig. 1.

Fig. 5 is a perspective view of the buckle employed for adjustably securing the pad to the insole.

Fig. 6 is a side view of a human foot showing the invention as it appears in use.

Fig. 7 is a top perspective view of the callus-protecting and arch-supporting pad.

Referring now to the drawings in which like reference numerals denote corresponding parts throughout the several views, the numeral 10 indicates a callus-protecting and arch-supporting pad, preferably circular in plan view, having a spherical top and a flat base, as clearly shown in Figs. 4 and 7. The pad 10 is provided with a central vertical rectangular aperture 11 for snugly receiving a buckle 12, by means of which the pad 10 is adapted to be secured at any desired adjusted position along an insole 13, preferably of leather. The upper portion of the pad 10 is provided with a pair of longitudinally extending alined recesses 14 and 15 for a purpose to be hereinafter described.

The insole 13 is preferably constructed from a relatively thick upper section 16 stitched or otherwise secured to a lower sec-

tion 17, the latter being provided near its rear end with a pair of spaced parallel slits 18 and 19, between which is a narrow central strip 20. The central strip 20 is reinforced and prevented from twisting out of shape by a metal stiffening band 21 running substantially the full length of the insole 13.

As most clearly shown in Fig. 5, the buckle for attaching the pad 10 to the strip 20 comprises a horizontal flat base 22 from which extend a pair of vertical side wings 23 and 24 and four end prongs 25, 26, 27, and 28, said prongs being bent longitudinally at their extremities to fit under the edges of the aperture 11 in the flat base of the pad 10. The bottom edges of the side wings 23 and 24 and the longitudinal extremities of said prongs are adapted to lie flush with the flat bottom surface of said pad 10, as clearly shown in Fig. 4.

In order to permit the pad to be securely held in any desired position along the length of the central strip 20, the buckle 12 is provided with an angular metal tongue 29 having a normally vertical gripping section 30 provided with a serrated edge 31 for engaging against said strip 20. The tongue 29 is also provided with an inclined flat web 32 having a slot 33 in its edge for permitting the insertion of the finger of the user for facilitating the swinging of said tongue from locked to unlocked position about the pivot pins 34 extending laterally from the angular tongue 29 and located in sockets 35 in the side wings 23 and 24.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an adjustable foot support adapted to be worn in a shoe under the foot, an insole, a pad located under said insole, a buckle carried by said pad and having its base connected to said insole, said buckle having a pivoted

tongue to detachably and adjustably secure said pad at any desired point under said insole.

2. In an adjustable foot support adapted to be worn in a shoe under the foot, an insole comprising upper and lower layers, a pad located under said insole, a buckle carried by said pad and having its base connected to the lower layer of said insole, said buckle having a pivoted tongue to detachably and adjustably secure said pad at any desired point under said insole.

3. In an adjustable foot support adapted to be worn in a shoe under the foot, an insole, a pad located under said insole, said pad having an aperture, a buckle carried by said pad and having its base connected to said insole, said buckle having a pivoted tongue to detachably and adjustably secure said pad at any desired point under said insole.

4. In an adjustable foot support adapted to be worn in a shoe under the foot, an insole, a pad located under said insole, said pad having a central rectangular aperture, a buckle carried by said pad and having its base connected to said insole, said buckle having a pivoted tongue to detachably and adjustably secure said pad at any desired point under said insole.

5. In an adjustable foot support adapted to be worn in a shoe under the foot, an insole comprising upper and lower layers, a pad located under said insole, a buckle carried by said pad and having its base connected to

the lower layer of said insole, said buckle having a pivoted tongue to detachably and adjustably secure said pad at any desired point under said insole, the base of said buckle having a pair of vertical side wings adapted to lie flush with the base of said pad.

6. In an adjustable foot support adapted to be worn in a shoe under the foot, an insole comprising upper and lower layers, a pad located under said insole, a buckle carried by said pad and having its base connected to the lower layer of said insole, said buckle having a pivoted tongue to detachably and adjustably secure said pad at any desired point under said insole, the base of said buckle having four holding lugs bent downwardly and longitudinally for clamping upon the flat under surface of said pad.

7. In an adjustable foot support adapted to be worn in a shoe under the foot, an insole comprising upper and lower layers, a pad located under said insole, a buckle carried by said pad and having its base connected to the lower layer of said insole, said buckle having a pivoted tongue to detachably and adjustably secure said pad at any desired point under said insole the base of said buckle having a plurality of holding lugs bent downwardly and longitudinally for clamping upon the flat under surface of said pad.

In testimony whereof, I have affixed my signature to this specification.

FRANK CALVO
